US0D1111873S

(12) **United States Design Patent** (10) Patent No.: **US D1,111,873 S**
(45) Date of Patent: ** Feb. 10, 2026

(54) **ALCOHOLOMETER**

(71) Applicant: **ETHYLOWHEEL**, Palaiseau (FR)

(72) Inventor: **Laurent Vermeglio**, Rueil-Malmaison (FR)

(**) Term: **15 Years**

(21) Appl. No.: **35/523,832**

(22) Filed: **Nov. 20, 2024**

(80) **Hague Agreement Data**

Int. Filing Date: **Nov. 20, 2024**

Int. Reg. No.: **DM/243548**

Int. Reg. Date: **Nov. 20, 2024**

Int. Reg. Pub. Date: **Jan. 31, 2025**

(30) **Foreign Application Priority Data**

May 21, 2024 (EM) 015061152-0001

(51) **LOC (15) Cl.** **10-04**

(52) **U.S. Cl.**

USPC **D10/78**; D10/81

Primary Examiner — Antoine Duval Davis

(57) **CLAIM**

The ornamental design for an alcoholometer as shown and described.

DESCRIPTION

1. Alcoholometer

1.1 : Right

1.2 : Front

1.3 : Top

1.4 : Top in perspective

1.5 : Bottom

1.6 : Bottom in perspective

The essential characteristics of the design are featured in its shape.

1 Claim, 6 Drawing Sheets
